UNITED STATES PATENT OFFICE.

BRICE W. HAVERFIELD, OF LA GRANGE, ILLINOIS.

DESIGN FOR A CABINET.

45,934.

Specification for Design.

Patented June 16, 1914.

Application filed September 17, 1913. Serial No. 790,371. Term of patent 7 years.

To all whom it may concern:

Be it known that I, BRICE W. HAVERFIELD, a citizen of the United States, and a resident of the city of La Grange, county of Cook, and State of Illinois, have invented a new, original, and ornamental Design for Cabinets, of which the following is a specification, reference being had to the accompanying drawing, forming a part thereof.

The figure of the drawing is a perspective view of a cabinet showing my new design.

I claim:

The ornamental design for a cabinet as shown.

In testimony whereof I have signed my name to this specification in the presence of two subscribing witnesses.

BRICE W. HAVERFIELD.

Witnesses:

ARTHUR A. OLSON,
B. G. RICHARDS.
